(57) **CLAIM**

The ornamental design for a winter car seat canopy, as shown and described.

DESCRIPTION

FIG. 1 is a perspective view of the winter car seat canopy, in an environment of use, showing the new design; FIG. 2 is a rear view of the winter car seat canopy thereof; FIG. 3 is a front view of the winter car seat canopy thereof; FIG. 4 is a left side view of the winter car seat canopy thereof; FIG. 5 is a right side view of the winter car seat canopy thereof; FIG. 6 is a top view of the winter car seat canopy thereof; and, FIG. 7 is a bottom view of the winter car seat canopy thereof. The small dash-dash lines represent stitching. The large dash-dash lines represent boundaries of the claimed design, environment of use, and zipper seam. Both the short dash-dash lines and long dash-dash lines form no part of the claimed design.
